UNITED STATES PATENT OFFICE.

WILLIAM GILFILLAN, OF NEW HAVEN, CONNECTICUT, ASSIGNOR TO SARGENT & CO., OF SAME PLACE.

PNEUMATIC DOOR-CHECK.

SPECIFICATION forming part of Letters Patent No. 311,742, dated February 3, 1885.

Application filed September 1, 1884. (No model.)

To all whom it may concern:

Be it known that I, WM. GILFILLAN, of New Haven, in the county of New Haven and State of Connecticut, have invented a new 5 Improvement in Door-Checks; and I do hereby declare the following, when taken in connection with accompanying drawings and the letters of reference marked thereon, to be a full, clear, and exact description of the same, 10 and which said drawings constitute part of this specification, and represent, in—

Figure 1, a view looking up toward the lintel of the door, showing the check as applied, the door in the closed position, broken lines 15 indicating the first part of the opening movement; Fig. 2, the same as Fig. 1, the door open; Fig. 3, a longitudinal sectional view, enlarged; Fig. 4, an outside view of the disk G; Fig. 5, an inside view of the disk H of the piston; Figs. 6 and 7, modifications of the valve devices.

This invention relates to a device having for its object to prevent the slamming of a door when forcibly closed, and usually employed in connection with a spring.

Various devices to check the closing door have been made, and in which a cylinder is employed, with a piston movable in the cylinder, to compress air therein as the door is closed. The air gradually escaping serves as a cushion to prevent the sudden closing or slamming of the door. Such checks are usually constructed so that they require to be applied near the hinge of the door. The momentum 35 of the door in closing under the action of a spring is very great. The check being applied near the hinge, the door under such momentum acts as a lever upon the hinge, the check being the fulcrum, and so near the hinge 40 that the power of the closing door upon the hinge is very great, and frequently breaks the hinge, or soon loosens the screws so as to derange the working of the hinge, and to such an extent is this difficulty experienced that 45 checks, otherwise satisfactory in their work, are dispensed with as a detriment, rather than advantage.

The object of my invention is the construction of a check which may be applied at any 50 point within the range of the swinging door, and so far from the hinge that the strain upon

the hinge heretofore experienced is avoided; and the invention consists, principally, in a cylinder open at one end combined with a piston and rod, the one—say the cylinder— 55 stationary, the other—say the piston and rod— applied to the door, and so that in opening the door the piston is drawn entirely from the cylinder and held in position to enter the cylinder as the door approaches its closed position, and as more fully hereinafter described. 60

A represents the cylinder, in size corresponding to the door to which it is to be applied. It is simply a straight cylinder, provided with ears B or other devices by which 65 it may be secured. The one end, C, is open, and made flaring to form the mouth or entrance to the cylinder. At the other end a cap, D, is applied, preferably, so as to screw onto that end of the cylinder, and upon its inside 70 it should be provided with a packing, E, say, a disk of leather, which may abut against the end of the cylinder. At one or more points in the outer surface of the cylinder a groove, a, is made, extending beyond the edge of the cap 75 D, and turned into the cylinder as at b, forming a passage from the inside of the cylinder outward. As the cap is screwed onto the cylinder to a greater extent the packing will be compressed, and correspondingly reduce the aperture b, or, loosened, will correspondingly extend that aperture by the cap D. Therefore the aperture b is made adjustable as to extent. Within the cylinder a piston is arranged upon 80 the end of a rod, F. The piston is best made 85 as seen in Fig. 3, and consists of a disk, G, slightly smaller than the internal diameter of the cylinder, and a second cup-shaped disk, H, between which a packing I is arranged, this packing, as here represented, consisting 90 of, say, a cup-shaped leather or other flexible material arranged between the disk G and the disk H, (shown in solid black in Fig. 3,) and so as to fit closely the interior of the cylinder, the cup shape inward or toward the closed 95 end. On the piston is a collar, L, and between the collar L and the disk G is an elastic collar, M. On the face of the disk G next the elastic collar M one or more radial grooves, d, are made, leading to the center, and through 100 the center around the piston corresponding longitudinal grooves, e, are made, as seen in

Fig. 4, which form a passage between the collar M and the disk G, thence through the disk G. Through the disk H longitudinal openings f are made, leading into radial 5 grooves h on the inner side of the disk H, as seen in Fig. 5. Onto the end of the piston a nut, N, is applied, which secures the piston to the rod. Thus constructed a passage is open between the collar M from the open end 10 of the cylinder through the piston to the other or closed end of the cylinder.

P is the bracket, to which the outer end of the piston-rod is hinged, as at i. On the piston-rod is an arm, R, extending to one side of 15 the pivot, and there provided with a spring, S, the tendency of which is to turn the arm from the bracket and correspondingly turn the piston-rod. From the opposite side of the piston-rod a similar arm, T, extends, and is 20 provided with a set-screw, U, which may take a bearing on the bracket and limit the extent of movement to which the spring may turn the piston-rod.

In illustrating the operation of my invention I show the piston-rod as attached to the 25 door and the cylinder to the lintel, and about midway the width of the door or little nearer the free edge of the door than the hinge, l representing the door, m the hinge, and n the 30 lintel. The cylinder and bracket are arranged, as seen in Fig. 1, so that the axis of the cylinder and piston are at substantially right angles to the door when the door is in its closed position. Thus attached the door is 35 opened until the piston just escapes from the end of the cylinder; then the set-screw U is turned until it comes to a bearing on the bracket, as indicated in broken lines, Fig. 1. The spring S, when the piston is free, holds 40 it in the position of the set-screw, bearing against the bracket. Therefore as the door continues its opening movement, as seen in Fig. 2, the piston retains its same relative 45 position to the door, and swings with it away from and independent of the cylinder. As the door is closed the piston approaches the cylinder in substantially a direct line, as indicated in broken lines, Fig. 1, and in the 50 position to properly enter the cylinder, the flaring mouth of the cylinder making the entrance easy. Thus the piston moves out of the cylinder in opening the door, and into it in closing the door. If the door be forcibly closed, as under the influence of a spring, or 55 a force of any character, the piston entering the cylinder cushions upon the air therein, the said cushion forming a resistance to the advance of the piston and causing the piston to lie against the elastic collar M. That collar 60 under such compression enters the passage d and closes it to prevent the escape of air within the cylinder outward through the piston. The air in the cylinder under the pressure of the piston is forced through the aperture b at 65 the closed end, and that being small, the escape is so slow that the inward movement of

the piston is retarded, and accordingly retards the final closing of the door, that final closing being only permitted as the air escapes through the aperture b. As before described, the aperture b may be adjusted to be larger or smaller. If larger, the air will sooner escape and permit the door to more quickly close. If it be smaller, the air will escape slower, and the closing of the door correspondingly retarded. 70 As the door is opened air may enter through the same aperture b to supply the cylinder; but were no other provision made there would be substantially the same resistance to the withdrawal of the piston as to its entering; 80 hence the first opening of the door would be resisted. To avoid this resistance, and make the opening of the door perfectly free, openings through the piston from the open end of the cylinder are provided. As the opening 85 movement of the door commences, the piston-rod starts first from the piston, owing to the elasticity of the collar M, thereby opening the passage d, which was closed when the piston entered, so that air may freely pass from the 90 open end of the cylinder through the piston and to the opposite end of the cylinder to supply air to the cylinder as the piston retreats. This supply is sufficient to permit the piston to be freely withdrawn from the cylinder, and so as to offer substantially no resistance to the opening of the door. 95

The construction of the check so as to permit the entire withdrawal of the piston from the cylinder and its due return thereto enables the check to be applied at any point between the free edge of the door and the hinge, and so far from the hinge that the sudden arrest of the closing door by the check produces no strain upon the hinge, and thereby overcomes a serious difficulty existing in this class of checks constructed so as to be applied only 105 near the hinge.

While I prefer to provide a supply of air to the cylinder for the withdrawal of the piston other than that which would naturally flow inward through the aperture b, such extra supply of air is not essential to my invention, as the simple aperture b may be sufficient; but in such case there will be some resistance to the first part of the opening of the door. 110

Instead of making the inlet for the air through the piston, it may be made in the form of a valve in the closed end of the cylinder, as seen in Fig. 6, the valve closing as the piston enters and opening as the piston withdraws, substantially as does the valve of a pump; or the inlet may be a simple valve upon the inner side of the piston, as seen in Fig. 7, which will open as the piston withdraws from and close as the piston enters the cylinder. The cup-shaped packing I permits the air to enter upon the inside of its flange, so as to force the packing against the cylinder 125 as the piston enters, and the flange will contract as the piston retreats. This cup-shaped 130

packing is, however, a well-known arrangement of packing for pistons, and while a good result is for a time attained in the employment of this packing, relying upon the compressed air to force the sides of the cup against the cylinder, after a little use the rim of the packing is liable to become so stiff as not to readily yield under the first impulse of compressed air; hence a portion of the air in the cylinder will be permitted to escape around the piston before the sides of the cup come to a bearing.

To insure the expansion of the sides of the cup, I arrange a ring-shaped spring, *n*, between the inner surface of the packing and the periphery of the collar *H*, and as seen in Figs. 3 and 5. This may be simply a divided ring, as seen in Fig. 5, or made in several pieces, in the usual manner of piston-springs. It expands against the inner surface of the flange or sides of the packing I sufficient to hold the outer surface of the packing I against the inner surface of the cylinder.

While I prefer to arrange the stopping device for the piston as by a spring, *S*, and the adjusting-screw *U*, the stop may be inadjustable and, say, consist simply of the arm *T*, dispensing with the arm *R*, the spring *S*, and the adjusting-screw *U*, and so that the piston will be stopped or prevented from turning upon its hinge at the instant it passes from the cylinder, the arm being arranged with relation to the bracket so as to come to a bearing thereon when this position is reached; but in that case care must be exercised in applying the check to see that the bracket and cylinder are so attached in their respective positions that the piston will be stopped as it passes from the cylinder in the opening of the door, and remain in that position until the door is closed, and so that the piston may surely return to the cylinder.

The aperture *b*, instead of being made directly in the cylinder, may be made through the cap on the end of the cylinder, as indicated in broken lines, Fig. 3; or it may be otherwise arranged, it only being essential that there shall be a small aperture from which the air in the cylinder compressed by the piston passing into the cylinder may slowly escape. Under this construction of check, which permits the piston to be drawn entirely from the cylinder, and consequently the arrangement of the check at a considerable distance from the hinge, the cylinder may be made very much smaller than the usual arrangement, where the check is applied near the hinge, and which on heavy doors makes the check anything but an ornamental attachment.

In applying the check, and in order to insure the proper relation of the bracket to the cylinder, I apply a wood disk, *J*, (see Fig. 6,) to the piston-rod at the mouth of the cylinder, and so that the piston standing at the inner end of the cylinder, the disk *J* forms a support for the piston at the other end, to hold it in its concentric position, and which position locates the bracket in its proper position for attachment with relation to the cylinder. With the two parts in that condition they are secured in their place, say, as seen in Fig. 1, then the door opened. The withdrawal of the piston from the cylinder will take with it the disk *J*. This disk, being of wood or other easily-destructible material, is readily removed from the rod, it having served its purpose as a guide or holder for the parts in their attachment.

I claim—

1. The combination of a cylinder, open at one end, closed at the other except as to a slight aperture, a piston arranged to work in said cylinder, and a bracket to which said piston-rod is hinged, said bracket and cylinder being constructed the one for attachment to the door and to swing with the door, the other constructed for stationary attachment, and so that the two may entirely separate, the piston provided with a stop to arrest its turning upon the hinge on the bracket as it leaves the cylinder, substantially as described.

2. The combination of the cylinder *A*, open at one end, the cap *D*, adjustable upon the opposite end, the said cylinder constructed with an aperture, *b*, beneath said cap, and which is adjustable by said cap, a piston in said cylinder, the bracket *P*, to which the piston-rod is hinged, the said bracket and cylinder, the one constructed for attachment to the door and the other for stationary attachment, and so that the two may entirely separate upon the opening of the door, and a stop to support said piston as it leaves the cylinder, substantially as described.

3. The combination of the cylinder *A*, open at one end, closed at the other except as to a small aperture, a piston in the cylinder, the bracket to which the piston-rod is hinged, said bracket and cylinder constructed the one for attachment to the door, the other for stationary attachment, and separating the one from the other in opening of the door, said piston constructed with an aperture from the open end of the cylinder to the reverse side of the piston, a valve arranged to close said aperture in the piston, and a stop to hold said piston as it leaves the cylinder, substantially as described.

4. The combination of the cylinder *A*, open at one end, closed at the opposite end except as to a small aperture, a piston in the cylinder, the bracket *P*, to which said piston is hinged, said bracket and cylinder constructed the one for attachment to the door, the other for stationary attachment, an adjustable stop, by which said piston is held as it passes from the cylinder, and a spring arranged to turn the piston toward and hold it upon said stop, substantially as described.

5. The combination of the cylinder *A*, constructed open at one end and closed at the opposite end except as to a small aperture, the bracket *P*, said bracket and cylinder con-

structed the one for attachment to the door, the other for stationary attachment, a piston within the cylinder, its rod hinged to said bracket, said piston consisting of the disks G 5 H and packing I, the said disks constructed with an aperture through them from the open side of the cylinder to the reverse side of the piston, the elastic collar M, and fixed collar L on the piston-rod, substantially as and for to the purpose described.

6. The combination of the cylinder A, constructed open at one end and closed at the opposite end except as to a small aperture, a bracket, P, said bracket and cylinder constructed the one for attachment to the door, the other for stationary attachment, a piston within the cylinder, its rod hinged to said bracket, said piston consisting of the disks G 15 H, cup-shaped packing I, and the spring i,

between the periphery of the said collar H 20 and the inner surface of said packing I, substantially as described.

7. The combination of a cylinder, open at one end, closed at the other except as to a slight aperture, a piston arranged to work in 25 said cylinder, a bracket to which said piston-rod is hinged, said bracket and cylinder being constructed the one for attachment to the door and to swing with the door, the other constructed for stationary attachment, and so 30 that the two may entirely separate, with the removable disk J, arranged upon the piston-rod, substantially as described.

WILLIAM GILFILLAN.
